(57) CLAIM

The ornamental design for a wave shaped food chopper, as shown and described.

DESCRIPTION

FIG. 1 is a front elevation view of a wave shaped food chopper showing my new design;

FIG. 2 is a rear elevation view thereof;

FIG. 3 is a side elevation view thereof, the broken lines showing a nesting straight edge chopper are for illustrative purposes only and form no part of the claimed design;

FIG. 4 is a top plan view thereof; and,

FIG. 5 is a bottom plan view thereof.
